UNITED STATES PATENT OFFICE.

CLINTON L. SAVIDGE, OF CALLAWAY, NEBRASKA.

VALVE COUPLING FOR TUBULAR WELLS.

Application filed November 8, 1921. Serial No. 513,801.

To all whom it may concern:

Be it known that I, CLINTON L. SAVIDGE, a citizen of the United States, residing at Callaway, in the county of Custer and State 5 of Nebraska, have invented certain new and useful Improvements in Valve Couplings for Tubular Wells, of which the following is a specification.

This invention relates to well apparatus 10 and the primary object of the invention is the provision of means for permitting the coupling of a lower or standing valve with the upper or working valve of a tubular well pump, so as to permit the simultaneous raising or lowering of said valves.

In well pumps the standing or lower valve and the plunger or working valve have no means of inter-connection so that it is necessary to have two distinct operations when 20 it is desired to pull the valves or to lower the valves in place.

In some instances, means is provided for permitting the valve to be screwed together, but this is impractical and has been abandoned by deep well men, as it has been found that when the pump rod becomes uncoupled from any cause whatever, from the working or plunger valve and it becomes necessary to screw the pump rod into the 30 valve again, the plunger or operating valve will engage and screw onto the lower or check valve. This of course, necessitates the pulling of both of the valves to permit the disconnection thereof.

It is therefore a prime object of the invention to provide a novel coupling for connecting the two valves together which will permit the simultaneous raising and lowering of the valve and free rotation of the 40 upper or plunger valve without the coupling of the lower or standing valve thereto.

A still further object of the invention is the provision of means for forming the coupling *per se*, so as to allow the ready 45 engaging and disengaging of the two parts and to insure the connection of the two parts against accidental displacement when the same are coupled together.

With these and other objects in view, the 50 invention consists in the novel construction, arrangement and formation of parts, as will be hereinafter more specifically described, claimed and illustrated in the accompanying drawings, forming a part of this specification, in which drawings;

Figure 1 is a side elevation of the upper

or working valve and the lower or standing valve operatively connected together and in a well casing, parts of the upper or working valve being shown in section.

Figure 2 is a detail perspective view of a lower end of the working or upper valve, and the upper end of the lower or standing valve showing the interlocking connection means carried by said valves.

Figure 3 is a detail horizontal section through the valve with the locking lugs in the guide slots prior to being turned to their locking position.

Figure 4 is a similar view showing the 70 lugs in their locking position.

Referring to the drawings in detail, wherein similar reference characters designate corresponding parts throughout the several views, the letter A indicates the upper or working valve; B, the lower or standing valve; and C a well casing.

The upper or working valve A is of the ordinary or any preferred construction with the exception of the means D carried thereby 80 for engaging the means E carried by the lower or standing valve B. This lower or standing valve B is of the usual or any preferred construction with the exception of the means E carried thereby.

The locking means D carried by the plunger or upper valve A consists of a depending sleeve 10, which may be formed integral with or secured in any preferred manner to the extreme lower end of the plunger or working valve A. The inner surface of the sleeve 10 is provided at diametrically opposite points with inwardly extending guide slots 11. These guide slots 11 communicate at their ends with oppositely directed locking slots 12, the lower faces of which are provided with locking notches 13, the purpose of which will be hereinafter more fully described. The lower ends of the opposite side walls of the guide slots 11 are provided with inclined or bevelled leading faces 14, the purpose of which will be hereinafter more fully described. The end walls of these slots also have their lower ends provided with similar guide faces 15.

The means E carried by the lower or standing valve for cooperating with the means D carried by the upper or operating valve A consists of a hollow stud 20 which may be internally threaded as at 21 for receiving the usual plunger rod. This is not necessary, however, as the plunger rod need

not be used to remove the lower valve as the same can be connected directly to the upper or working valve as heretofore described. The outer face of the stud 20, which is connected in any preferred manner to valve B is provided with oppositely directed diametrically opposed locking lugs 22, which are of a size as to readily fit within the guide slots 11, the locking slots 12 and the locking notches 13. The guide walls 14 and 15 are provided in order to facilitate the guiding of the entrance of the lugs into the guide slots 11.

In use of the improved well valve puller, when it is desired to raise or pull both of the valves A and B, it is merely necessary to move the valve A into engagement with the valve B and give the same a slight turning motion until the lugs 22 come into alignment with the guide slots 11. The valve A can then be lowered a little more and given a turn in a counter-clockwise direction, which will effectively move the lugs 22 within the slots 12. Upon movement of the valve A, the lugs 22 will seat into the locking notches 13, and the accidental displacement of the valves A and B will be prevented and the valve B will be moved with the valve A. When the valves reach the top of the well, they can be readily and quickly disconnected. When it is desired to lower the valves in the well casing C, it is merely necessary to connect the valves together by hand and then lower the valves into their respective positions. When the valve B

reaches its position in the casing, the valve A is given a slight turn by the plunger rod until the lugs 20 ride into engagement with the guide slots and at which time the valve A is raised and the lugs will ride off of engagement with the valve B. The valve A is then free from movement independently of the valve B.

Changes in details may be made without departing from the spirit or scope of this invention; but,

I claim:

The combination with an upper working valve, a lower standing valve, of means for permitting the detachable connection thereof including a depending sleeve carried by the upper operating valve, the sleeve having inwardly extending diametrically opposed guide slots formed in the walls thereof, and oppositely disposed circumferentially extending locking slots communicating with the upper ends of the guide slots, said sleeve also having formed therein downwardly extending locking notches at the terminals of the locking slots arranged in parallel relation to the guide slots, an upwardly extending hollow and internally threaded stud formed on the standing valve, radially extending lugs formed on the stud for engaging in said guide slots, the locking slots and notches, the side and end walls of the guard slots being inclined to provide a guide surface for said lugs.

CLINTON L. SAVIDGE.
